United States Patent Office

Des. 196,594
Patented Oct. 15, 1963

196,594

CHILD'S CLIMBER

James Fernan and Mildred Louise Fernan, both of
9811 Belmont, Kansas City, Mo.

Filed Dec. 12, 1961, Ser. No. 67,871

Term of patent 14 years

(Cl. D34—5)

Fig. 1.

Fig. 4.

Fig. 2.

Fig. 3.

FIG. 1 is a perspective view of a child's climber, showing our new design;

FIG. 2 is an end elevational view thereof;

FIG. 3 is a side elevational view of one side of the child's climber; and

FIG. 4 is a top plan view as seen along the line 4—4 of FIG. 3 with top board and climbing rope omitted for convenience of illustration.

We claim:

The ornamental design for a child's climber, as shown and described.
